FIG. 5.

UNITED STATES PATENT OFFICE.

JOHN PURDY, OF NEW YORK, N. Y., ASSIGNOR TO THE MONARCH TYPEWRITER COMPANY, OF SYRACUSE, NEW YORK, A CORPORATION OF NEW YORK.

TYPE-WRITING MACHINE.

1,023,172.

Specification of Letters Patent. Patented Apr. 16, 1912.

Application filed December 11, 1911. Serial No. 664,991.

To all whom it may concern:

Be it known that I, JOHN PURDY, a citizen of the United States, and resident of the borough of Brooklyn, city of New York, in the county of Kings and State of New York, have invented certain new and useful Improvements in Type-Writing Machines, of which the following is a specification.

My invention relates to typewriting machines and more particularly to machines for preparing or "writing" stencil plates or cards, and the object of the invention, generally stated, is to provide comparatively simple and efficient means of the character specified and by which the stencil plates or cards may be quickly introduced into the machine and properly squared and positioned to receive the first line of writing and may be introduced into and fed through the machine in a flat condition.

To the above and other ends which will hereinafter appear, my invention consists in the features of construction, arrangements of parts and combinations of devices described in the following specification and particularly pointed out in the appended claims.

In the accompanying drawings wherein like reference characters indicate corresponding parts in the various views, Figure 1 is a fragmentary front elevation showing the upper portion of a typewriting machine embodying my invention. Fig. 2 is a fragmentary side elevation of the same with parts in section. Fig. 3 is a fragmentary detail perspective view of one of the feed rollers and some of the associated parts. Fig. 4 is a fragmentary detail perspective view of the release key and some of the associated parts. Fig. 5 is a detail perspective view of the side edge gage.

I have shown my invention in the present instance embodied in a Monarch machine and have only shown so much of said machine as may be necessary to arrive at an understanding of my invention. It should be understood, however, that the invention may be embodied in various styles of typewriting machines employing a cylindrical or rotative platen.

The frame of the machine comprises corner posts 1 surmounted by a top plate 2. Fixed oppositely grooved guide rails 3 are

secured to standards 4 by screws 5. These standards are fixed to and project upwardly 55 from the top plate of the machine and are adapted to support the carriage in its movement from side to side of the machine over the top plate. The carriage comprises a guide bar 6 oppositely grooved at the top 60 and bottom thereof to receive anti-friction balls or rollers 7 which are likewise received in the oppositely grooved bearings in the fixed guide rails 3. The guide bar 6 constitutes a rear cross bar of the carriage from 65 which project forwardly extending side or end bars 8, provided with bearings to receive a platen shaft 9 on which a cylindrical rotative platen 10 is mounted. It will be understood that the carriage in its movement over the top plate is impelled by the usual carriage spring (not shown) and is controlled by the usual escapement mechanism which I have not deemed it necessary to illustrate. A line spacing movement 70 may be transmitted to the platen by the usual means co-operative with a line spacing wheel 11 to effect a step-by-step rotative movement of the platen. Projecting upwardly from the end bars 8 of the carriage 75 are the usual lugs 12 and 13 apertured to receive the ends of a rod 14 fixed in its bearings and held in position by screws 15 and 16. This cross bar supports the usual erasing shelf 17 and margin paper fingers and 80 feed rollers 18 and 19 respectively. A combined platen and carriage scale plate 20 is supported in the usual manner beneath the printing line, indicated at *a*.

The construction thus far described constitutes part of the ordinary equipment of the Monarch machine and further detailed description thereof is deemed unnecessary, it being understood that the usual upwardly and rearwardly swinging type bars are 90 adapted to strike against the front face of the platen.

I have provided the following additional or supplementary equipment by which the machine may be readily converted into a machine for preparing or "writing" stencil plates and by which the stencil plates may be properly positioned in the machine to receive the first line of "writing" and may be introduced, positioned and fed through 105 the machine in a flat condition. An auxil-

ary plate, 21 is secured to the usual depending lugs 22 on the top plate by headed screws 23 received in tapped openings in the lugs. The upper edge of the plate 21 is bent forwardly at right angles to the body portion thereof to present a horizontally disposed shelf-like support 24 which extends longitudinally of the platen, throughout the length of the plate 21 and throughout a considerable portion of the length of the platen. This shelf-like support is arranged in front of the platen and directly beneath the printing line, as indicated in Fig. 2, and extends forwardly of the scale plate 20 where it is adapted to coöperate with the bottom edge of a card or stencil plate designated as a whole by the reference numeral 25. These stencil plates are ordinarily made with a comparatively thick rectangular pasteboard frame 26 which is covered by a comparatively thin stencil sheet 27.

It will be seen upon reference to Figs. 1 and 2 that when the stencil plate or card is introduced into the machine the bottom edge thereof is squared and properly positioned against the support 24 which is carried by the top plate of the machine, and that when thus squared the stencil plate is in a position to receive the first line of "writing" thereon. It will be seen moreover, that the stencil plate is maintained in a flat condition in front of the platen and, as will hereinafter more clearly appear, may be fed in such condition upwardly during the line spacing movement of the platen. The plate 21 is apertured at 28 to enable a vibrator lever 29 to project therethrough. A plate 30 is secured by a screw 31 to the plate 21. This plate 30 is likewise apertured at 32 to register with the opening 28 to receive the vibrator lever 29 therethrough. The plate 30 is bent forwardly at 33 beneath the card support and extends upwardly at 34 above the card support to form a pointer which is in alinement with the printing point, indicated at X in Fig. 1. This pointer performs a two-fold function; thus it indicates on the stencil plate the printing point and at the same time constitutes means for preventing the stencil plate from being displaced forwardly at the bottom edge thereof from the support 24. It also coöperates with the scales on the scale plate 20 when a stencil plate is removed from the machine in order to indicate the position of the carriage in its line of travel.

From an inspection of Figs. 1 and 2 it will be seen that a sheet metal bracket 35 is secured to the upwardly extending lug 12 on the right-hand end bar of the carriage by the screw 15 which secures the cross bar or rod 14 in position. This bracket plate is bent at right angles to its length, as indicated at 36, so as to pass through the inner side of the right-hand end bar 8, and is se-

cured thereto at its forward end by a screw 37. An upwardly extending arm 38 of the bracket 35 has a headed pivot 39 riveted thereto. This pivot, as will be seen upon reference to Fig. 4, is received in a bearing opening 40 in a yoke-like member 41, one arm of the yoke being extended downwardly and rearwardly to form an arm 42 which terminates in a finger piece or key 43 by which the yoke may be turned on its pivot 39. A headed pin 44 extends laterally from the arm 42 and is engaged by one end of a wire spring 45. This spring is coiled about a headed pin 46 which projects inwardly from the bracket arm 38. The opposite end 80 of the spring is bent to the right at 47 where its rests against the bottom portion of the bracket 35, so that the force of the spring is exerted to tend to move the arm 42 upwardly and to turn the yoke-like member 41 85 in the direction of the arrow in Fig. 4. A splined rock shaft or rod 48 is received in an opening in the arm 42 of the yoke, such opening corresponding in shape to the cross section of the splined rock shaft. From an inspection of Fig. 4 it will be understood that the axial center of the rock shaft is in alinement with the axis of the pivot 39 and that the spline 49 connects the rock shaft to the yoke 41 and arm 42 to turn therewith. 95 This splined rock shaft is arranged above the platen and above the front face thereof and extends throughout the length of the carriage and is received at its opposite end in a bearing opening in a sheet metal bracket 100 50. The bearing opening in the bracket 50 is cylindrical and the end of the spline 49 bears against the inner face of the bracket to limit the longitudinal movement of the rock shaft to the left.

From an inspection of Fig. 1 it will be seen that the longitudinal movement of the rock shaft 48 to the right is limited by the right-hand end thereof abutting the headed pivot 39. The bracket 50 has a foot piece 110 51 formed thereon and bearing against the top of the left-hand end bar 8 of the carriage, in order to support the forward end of the bracket. The bracket extends rearwardly and is connected at its rear end to 115 the carriage by the screw 16 which connects the cross bar 14 to the carriage.

From the foregoing description it will be understood that the right-hand supporting bracket 35 for the splined rock shaft is secured at both the front and rear ends thereof by screws 37 and 15 respectively, whereas the left-hand bracket 50 is secured only at the rear end thereof by the screw 16. This manner of connecting the two brackets 125 therefore is effective to rigidly secure the right-hand bracket to the carriage, but to secure the left-hand bracket in such a manner that the forward end thereof may be slightly flexed to the left in order to dis- 130

engage it from the left-hand end of the rock shaft 48 and enable the shaft to be withdrawn from the bearing on the yoke 41 at the right-hand end of the rod.

- 5 Two sheet metal hangers, each designated as a whole by the reference numeral 52, are mounted for a limited pivotal movement on the splined rock shaft 48. Referring more particularly to Fig. 3 it will be seen that 10 each hanger is provided with parallel ears 53 having cylindrical bearing openings 54 for the reception of the body of the splined rock shaft 48. Each ear is likewise apertured at 55 to receive the spline 49 on the shaft. 15 Each aperture 55 is wider than the thickness of the spline in order that a slight pivotal movement of the hanger may be effected independently of the rock shaft. A leaf spring 56 bears at its free end against 20 the forward edge of the spline 49 and the spring is looped at 57 and is perforated to receive freely therethrough a screw 58. The body portion of the hanger 52 is likewise perforated to receive the screw freely 25 therethrough; the head 59 of the screw bearing against the rear side of the hanger, whereas a nut 60 is threaded onto the forward end of the screw. By adjusting each nut 60 toward the head of the screw the 30 looped portion of the spring may be flexed to increase the pressure of the spring on the spline. It will be seen that by this arrangement an individual adjusting means is provided for each hanger, and that each 35 hanger may be moved toward and away from the platen against the pressure of the spring 56 independently of the other, for purposes which will hereinafter more clearly appear. Each hanger carries an inwardly 40 off-set margin feed roller 61 connected to the hanger by a headed pivot screw 62, received at its threaded end in a tapped opening in the block-like portion 63 on the hanger. Each margin feed roller as shown 45 in the present instance comprises a metal roller having a knurled periphery and an outwardly extending hub 64. The tread of each feed roller is therefore off-set inwardly from the hanger which carries it. These 50 rollers are preferably arranged in front of the platen adjacent to the printing line in a position where they are adapted to operate with the side edge portions of a stencil plate, while the latter is maintained 55 in a flat condition in front of the platen and at the printing line, and while it is supported on the stencil plate or card support 24. In the present instance the rollers bear against the platen above the printing line a 60 short distance.

Soldered or otherwise connected to the inner ear 53 of each hanger is a plate 65 provided with an inwardly off-set bent arm 66. This arm is prolonged to form a deflecting 65 finger 67 which extends from the front of

the rock shaft or rod 48 downwardly and rearwardly toward the platen, said finger terminating adjacent to the platen as shown in Fig. 2. Each finger 67 stands at an inclination to the plane of the stencil plate 70 or card when the latter is properly positioned in the machine. Each deflecting finger 67 is also arranged in position where a vertical fore and aft plane extending through the tread of the associated feed 75 roller will likewise extend longitudinally through the deflecting finger. It will be seen therefore that the deflecting fingers are in positions where they will co-act with the upper or leading edge of the card or 80 stencil plate near the side members of the frame thereof and in rear of the stencil plate to deflect the upper edge thereof forwardly to clear the rock shaft 48 and to cause the card to pass upwardly in front 85 of said rock shaft.

It will be understood that the construction is such that each hanger, and the deflecting finger 67 which is connected therewith, is capable of being adjusted on the rock shaft 90 48 longitudinally thereof in order that the margin feed rollers may, if desired, be adjusted to different positions longitudinally of the platen, so as to present different lengthwise portions of the platen to the impact of the types. To maintain the hangers and margin feed rollers against relative adjustment longitudinally of the platen I have connected the hangers by a flexible metal strip 68 which extends longitudinally of the 100 platen and may be connected at each end to a hanger by solder or other suitable character of connection. This strip therefore maintains a fixed relation between the margin feed roller 61 and between the deflecting fingers 67, considered longitudinally of the platen, although the connecting strip 68 does not prevent a relative and limited pivotal movement of the hangers and the parts carried thereby by reason of the flexible nature of the strip. The connecting strip 68 however does not prevent the hangers and the parts carried thereby from being adjusted to different positions longitudinally 105 of the platen if desired; but merely maintains them properly spaced apart to coöperate with a stencil plate of a given size in order that the feed rollers and deflecting fingers may co-act with the frame 26 of the stencil plate and not with the covering 27 110 thereon where it spans the rectangular opening in the frame.

It should be understood that the rock shaft 48 is turned by the spring 45 to exert the force of said spring through the margin 125 feed roller 61 against the side bars of the stencil plate or frame, but that, nevertheless, any inequalities in one side of the frame will cause the margin feed roller 61 which coöperates therewith to be deflected away 130

from the platen against the force of its spring 56 without causing a corresponding movement of the other margin feed roller. The margin feed rollers therefore act under the force of the spring 45 to bear against the frame of the stencil sheet or plate and each roller also acts individually against the frame under the force of its spring 56. By this construction an efficient self-regulating feed may be effected for the stencil plates and each stencil plate is compressed by the margin feed rollers against the face of the platen near the printing line in order to effect an upward feed of a stencil plate while it is maintained in a flat condition. The deflecting fingers 67 assure a feed of the stencil plate to the forward side of the rock shaft 48 where the rock shaft does not constitute an obstruction to the operator's view of the plate as the "writing" proceeds.

If at any time it is desired to release the pressure of the margin feed rollers on a stencil plate a depression of the finger piece 43 is effective to turn the rock shaft 48 and to turn the hangers so as to relieve the pressure of the margin feed rollers on the stencil plate.

It will be understood that the fixed shelf-like supporting member 24 is separate from the means for guiding and feeding the stencil plate in the line feed movement of the latter, and is likewise supported independently of the means by which the stencil sheet is fed and guided in its line spacing movement; that the feed rollers 61 are separate from the support 24 by which the lower edge of the card is supported and that said feed rollers are also supported independently of the support 24 by which the card or stencil plate is supported in position when it is first introduced into the machine. It will also be seen that the construction is such that it is in the nature of an attachment which may be readily applied to existing forms of machines such as the Monarch machine without modifying the structural features of that machine and that when the rock shaft 48 is detached from its supporting bracket 50 and from the yoke 41 the carriage is in condition for ordinary use. While the paper fingers 18 and margin feed rollers 19 of the ordinary equipment are not employed when the machine is used for stencil work, I have shown these parts in order to indicate that the carriage may be quickly adapted for ordinary use and that it is unnecessary to remove the ordinary equipment on the carriage in order to employ the devices of my invention thereon. When the rod 48 and the parts carried thereby are removed in the manner described, and the plate 21 is detached and replaced by the ordinary front plate of a Monarch machine which carries ribbon vibrator equipment, the ma-

chine will be in condition for ordinary use 65 for correspondence and the like.

I have provided a side edge gage, which is shown in detail in Fig. 5, to aid in properly positioning the stencil plates in the machine. This side edge gage is designated 70 as a whole by the reference numeral 69 and comprises an angular plate, one of the angular members 70 of which is in a plane at right angles to the axis of the platen and is in position to coöperate with the right-hand side edge of a stencil plate or card when the latter is introduced into the machine, as shown in Fig. 1. The other angular portion of the side edge gage is arranged to overlap and rest on the looped 80 portion of the right-hand spring 56, and is perforated to receive a screw 58 therethrough. The associate nut 60 bears on top of the gage and secures it in place. It will be seen that the gage is thus carried by the 85 right-hand hanger 52 and maintains a fixed relation with reference to the margin feed rollers 61 and the deflecting fingers 67, considered longitudinally of the platen. Any adjustment of the margin feed rollers and 90 deflecting fingers brings about a corresponding adjustment of the side edge gage, so that it is at all times in a position to properly coöperate with the right-hand side edge of a stencil plate irrespective of the position 95 to which the feed rollers may be adjusted longitudinally of the platen. It will also be understood that the contact face of the side edge gage is in a plane which is at right angles to the plane of the contact face of the support 24 for the stencil plates, so that the contact face on the side edge gage and the contact face on the support 24 coöperate with edges of the stencil plate which are at right angles to each other, to properly 100 square the plate when it is introduced into the machine both horizontally and vertically and obtain a proper positioning of the stencil plate with reference to the printing line and with reference to the feeding and guiding devices which coöperate with the stencil 110 plate.

From the foregoing description it will be understood that I have provided simple and efficient devices that are readily adapted to 115 the Monarch machine without changing the structural features of that machine; that the embodiment of these devices in the machine provides means by which stencil plates may be readily introduced and properly 120 squared and positioned in the machine in a flat condition; that the stencil plates may be fed in such condition during the line spacing movements of the platen and that it is by the feed movements of the platen 125 that the stencil plates are fed to receive the different lines of "writing."

Various changes may be made without

departing from the spirit and scope of my invention.

What I claim as new and desire to secure by Letters Patent, is:—

5. 1. In a front-strike typewriting machine, the combination of a carriage, a rotative platen, supporting means coöoperative with the bottom edge of a card for squaring the card and supporting it in a flat condition 10 in front of the platen and at the printing line, and spring-pressed margin feed rollers arranged in front of the platen and adjacent to the printing line and coöoperative with a card near the side edge portions thereof, said feed rollers being independent of said supporting means and independent of the means by which said supporting means receives its support.

2. In a front-strike typewriting machine, 20 the combination of a carriage, a rotative platen, supporting means coöoperative with the bottom edge of the card for squaring the card and supporting it in a flat condition in front of the platen and at the printing 25 line, contact devices arranged in front of the platen adjacent to the printing line and coöoperative with a card near the side edge portions thereof, said contact devices being independent of said supporting means and 30 independent of the means by which said supporting means receives its support, and deflecting fingers which are arranged above said contact devices and extend downwardly and rearwardly toward the platen and 35 operate with the upper edge of the card at the rear side thereof.

3. In a front-strike typewriting machine, the combination of a carriage, a rotative platen, supporting means coöoperative with 40 the bottom edge of the card for squaring the card and supporting it in a flat condition in front of the platen and at the printing line, a rod detachably connected to the carriage and separate from said card sup- 45 porting means and separate from the means by which the card supporting means is supported, and spring-pressed feed devices arranged in front of the platen adjacent to the printing line and coöoperative with the 50 card near the side edge portions thereof, said feed devices being carried by and detachable with said rod.

4. In a front-strike typewriting machine, 55 the combination of a carriage, a rotative platen, supporting means coöoperative with the bottom edge of a card for squaring the card and supporting it in a flat condition in front of the platen and at the printing line, a rod carried by the carriage and separate 60 from the card supporting means and separate from the means by which the card supporting means is supported, feed devices arranged in front of the platen adjacent to the printing line and coöoperative with a 65 card near the side edges thereof, and in-

clined deflecting fingers carried by said rod and coöoperative with the card to guide it to the front of said rod.

5. In a front-strike typewriting machine, 70 the combination of a carriage, a rotative platen, supporting means coöoperative with the bottom edge of a card for squaring the card and supporting it in a flat condition in front of the platen and at the printing line, a rod detachably connected to the carriage and separate from the card supporting means and the means by which said card supporting means is supported, spring-pressed margin feed rollers carried by and detachable with said rod, said margin feed 75 rollers being arranged in front of the platen adjacent to the printing line, and inclined deflecting fingers which are carried by and are detachable with said rod and extend downwardly and rearwardly therefrom 80 toward the platen and coöperate with the upper edge of a card to guide it in front of said rod.

6. In a front-strike typewriting machine, 85 the combination of a carriage, a rotative platen carried thereby, a support arranged in front of the platen and beneath the printing line, said support being operative to support a card or the like at the bottom edge thereof while the card is maintained 90 in a flat condition in front of the platen at the printing line, margin feed rollers which are separate from said card support and which are supported independently thereof, said margin feed rollers being coöoperative 95 with the card near the side edges thereof, and mounted for movement toward and away from the platen, and spring means for moving said rollers toward the platen and for exerting a spring force through the rollers 100 against the card.

7. In a front-strike typewriting machine, 105 the combination of a carriage, a rotative platen carried thereby, a substantially horizontally disposed shelf-like support arranged in front of the platen and beneath the printing line and extending longitudinally of the platen, said support being operative to support a card or the like at the bottom edge thereof while the card is maintained 110 in a flat condition in front of the platen and at the printing line, margin feed rollers which are separate from said shelf-like support and which are supported independently thereof, said margin feed rollers 115 being coöoperative with a card near the side edges thereof and mounted for movement toward and away from the platen, and spring means for moving said rollers toward the platen and for exerting a spring force 120 through the rollers against the card.

8. In a front-strike typewriting machine, 125 the combination of a carriage, a rotative platen carried thereby, a support arranged in front of the platen and beneath the print-

ing line, said support being operative to support a card or the like at the bottom edge thereof while the card is maintained in a flat condition in front of the platen and at the printing line, margin feed rollers which are separate from said card support and which are supported independently thereof, a rod on which said rollers are supported and means independent of said rod for operatively connecting said rollers to prevent a relative movement thereof longitudinally of said rod.

9. In a front-strike typewriting machine, the combination of a carriage, a rotative platen carried thereby, a support arranged in front of the platen and beneath the printing line, said support being operative to support a card or the like at the bottom edge thereof while the card is maintained in a flat condition in front of the platen and at the printing line, margin feed rollers which are separate from said card support and which are supported independently thereof, said margin feed rollers being adjacent to the printing line and being co-operative with the card near the side edges thereof, and means for operatively connecting said rollers to prevent relative movement between them longitudinally of the platen but to afford relative movement between the rollers toward and away from the platen.

10. In a front-strike typewriting machine, the combination of a carriage, a rotative platen carried thereby, a support arranged in front of the platen and beneath the printing line, said support being operative to support a card or the like at the bottom edge thereof while the card is maintained in a flat condition in front of the platen and at the printing line, margin feed rollers which are separate from said card support and which are supported independently thereof, said margin feed rollers being co-operative with the card near the side edges thereof and mounted for movement toward and away from the platen, and a flexing connection between said rollers for connecting them against relative movement longitudinally of the platen but affording a relative movement between the rollers toward and away from the platen.

11. In a front-strike typewriting machine, the combination of a carriage, a rotative platen carried thereby, a support arranged in front of the platen and beneath the printing line, said support being operative to support a card or the like at the bottom edge thereof while the card is maintained in a flat condition in front of the platen at the printing line, margin feed rollers which are separate from said card support and which are supported independently thereof, said margin feed rollers being co-operative with the card near the side edges thereof, independent pivoted spring-

pressed supporting members for said rollers, and a resilient strip which extends longitudinally of the platen and connects said supporting members to prevent a relative movement between the members longitudinally of the platen but to afford a relative movement between the members toward and away from the platen. 70

12. In a front-strike typewriting machine, the combination of a carriage, a rotative platen carried thereby, a support arranged in front of the platen and beneath the printing line, said support being operative to support a card or the like at the bottom edge thereof while the card is maintained in a flat condition in front of the platen and at the printing line, a supporting rod, hangers independent of said card support and mounted on said rod for pivotal movement, an independent spring for each hanger to force it independently of the other hanger toward the platen, and an offset inwardly extending margin feed roller mounted on each of said hangers, said feed rollers being co-operative with the card near 80 the side edges thereof. 85

13. In a front-strike typewriting machine, the combination of a carriage, a rotative platen carried thereby, a support arranged in front of the platen and beneath the printing line, said support being operative to support a card or the like at the bottom edge thereof while the card is maintained in a flat condition in front of the platen and at the printing line, a spring turned rock shaft, hangers independent of said card support and mounted on said rock shaft for a limited pivotal movement thereon, an independent spring for each hanger to force one of the hangers independently of the other toward the platen, an off-set inwardly extending margin feed roller mounted on each of said hangers, said feed rollers being co-operative with a card near the side edges thereof, and a finger piece connected with said rock shaft and operative to turn it to release the feed rollers from the platen or the card with which they co-operate. 95 100 105 110

14. In a front-strike typewriting machine, the combination of a carriage, a rotative platen carried thereby, a support arranged in front of the platen and beneath the printing line, said support being operative to support a card or the like at the bottom edge thereof while the card is maintained in a flat condition in front of the platen at the printing line, a splined rod, hangers independent of said card support and mounted on said splined rod for a limited pivotal movement thereof, an independent spring for each hanger, each spring co-operating with the spline to force the associated hanger toward the platen, an off-set inwardly extending margin feed roller 115 120 125 130

mounted on each of said hangers, said feed rollers being coöperative with a card near the side edges thereof, an operative connection between said hangers to prevent a relative movement between them longitudinally of the platen, and a finger piece connected with said splined rod and operative to turn it to release the feed rollers from the platen or the card with which they coöperate.

10 15. In a front-strike typewriting machine, the combination of a carriage, a rotative platen carried thereby, a support arranged in front of the platen and beneath the printing line, said support being operative to support a card or the like at the bottom edge thereof while the card is maintained in a flat condition in front of the platen at the printing line, margin feed rollers which are separate from said card support and which are supported independently thereof, said margin feed rollers being coöperative with a card near the side edges thereof and being mounted for movement toward and away from the platen, spring 25 means for moving said rollers toward the platen and for exerting a spring force through the rollers against the card, and independently adjustable means for said spring means to afford an independent adjustment of the pressure on each roller.

16. In a front-strike typewriting machine, the combination of a carriage, a rotative platen carried thereby, a support arranged in front of the platen and beneath the printing line, said support being operative to support a card or the like at the bottom edge thereof while the card is maintained in a flat condition in front of the platen and at the printing line, margin feed 30 rollers which are separate from said card support and which are supported independently thereof, said margin feed rollers being coöperative with the card near the side edges thereof, a finger piece, and means controlled thereby for simultaneously releasing both of said feed rollers.

17. In a front-strike typewriting machine, the combination of a carriage, a rotative platen carried thereby, a substantially 50 horizontally disposed supporting shelf carried by the frame of the machine and arranged below the printing line and coöperative with the bottom edge of a card or the like to support it in a flat condition in front 55 of the platen and at the printing line, and margin feed rollers carried by the carriage and coöperative with the side edge portions of a card or the like when the same is in position at the printing line, a spring pressed 60 pivoted supporting rod arranged above the platen, and a pair of carriers carried by said rod, the margin feed rollers being carried by said carriers.

18. In a front-strike typewriting machine, 35 the combination of a carriage, a rotative

platen carried thereby, a support arranged in front of the platen and beneath the printing line, said support being operative to support a card or the like at the bottom edge thereof while the card is maintained in a flat condition in front of the platen at the printing line, margin feed rollers coöperative with the card near the side edges thereof, and inclined deflecting fingers arranged above the feed rollers and coöperative with the upper edge of the card at the rear side thereof.

19. In a front-strike typewriting machine, the combination of a carriage, a rotative platen carried thereby, a support arranged in front of the platen and beneath the printing line, said support being coöperative to support a card or the like at the bottom edge thereof while the card is maintained in a flat condition in front of the platen and at the printing line, margin feed rollers which are separate from said card support and which are supported independently thereof, a rod carried by the carriage and which constitutes a support for said feed rollers, and inclined deflecting fingers which coöperate with the upper edge of the card to direct it in front of said rod.

20. In a front-strike typewriting machine, the combination of a carriage, a rotative platen, a supporting rod carried by the carriage above the platen, inclined deflecting fingers which extend downwardly and rearwardly from said rod to coöperate with the upper edge of the card at the rear side thereof and direct the card upwardly in front of said rod, margin feed rollers arranged in front of the platen and coöperative with the card near the side edges thereof, and a card support independent of said deflecting fingers and independent of the means for supporting the margin feed rollers for supporting a card at the bottom edge thereof, said card support being operative to support a card or the like in a flat condition in front of the platen and at the printing line.

21. In a front-strike typewriting machine, the combination of a carriage, a rotative platen, a supporting rod carried by the carriage above the platen, inclined deflecting fingers which extend downwardly and rearwardly from said rod toward the platen and to a point above the printing line, said fingers coöperating with the upper edge of the card at the rear side thereof to cause the upper or leading edge of the card to be deflected to the front of said rod, margin feed rollers carried by said rod and arranged near the printing line, and means for supporting the card in a flat condition in front of the platen and at the printing line.

22. In a front-strike typewriting machine, the combination of a carriage, a rotative platen, means independent of the platen and

fixed against line feed movement therewith for supporting a card or the like in a flat condition in front of the platen and at the printing line, means for feeding the card 5 upwardly in a flat condition and away from said card supporting means, and a side edge gage coöperative with a side edge of the card when it is positioned upright in front of the platen.

10 23. In a front-strike typewriting machine, the combination of a carriage, a rotative platen, means for supporting a card or the like in a flat condition in front of the platen and at the printing line, margin feed rollers 15 adjacent to the printing line and coöperative with the side edge portions of the card for feeding the card upwardly in a flat condition, and a side edge gage carried by a support for one of said feed rollers and co- 20 operative with a side edge of the card when it is positioned upright in front of the platen.

24. In a front-strike typewriting machine, the combination of a carriage, a rotative platen, means coöperating with the bottom 25 edge of a card for supporting it in a flat condition in front of the platen and at the printing line, a pointer arranged in front of the card and operative to prevent the card

from moving forwardly off its supporting means, margin feed rollers adjacent to the printing line and coöperative with the side edge portions of the card for feeding the card upwardly in a flat condition, and a side edge gage coöperative with a side edge 55 of the card when it is positioned upright in front of the platen.

25. In a front-strike typewriting machine, the combination of a carriage, a rotative platen carried thereby, engaging means independent of the platen and fixed against line feed movement therewith for engaging a card on two sides thereof at right angles to each other and squaring the card and supporting it in a flat condition in front of the platen and at the printing line, and means coöperative with the platen to feed the card upwardly in a flat condition independently of said engaging means.

Signed at the borough of Manhattan, city 50 of New York, in the county of New York, and State of New York, this 8th day of December, A. D. 1911.

JOHN PURDY.
